Ark.

Application September 19, 1933, Serial No. 690,123

1 Claim. (Cl. 81—55)

This invention relates to a wrench, the general object of the invention being to provide a wrench for use on lug nuts of dual truck wheels.

This invention also consists in certain other features of construction and in the combination and arrangement of the several parts, to be hereinafter fully described, illustrated in the accompanying drawing and specifically pointed out in the appended claim.

10 In describing the invention in detail, reference will be had to the accompanying drawing wherein like characters denote like or corresponding parts throughout the several views, and in which:—

15 Figure 1 is an elevation with parts in section of the improved wrench.

Figure 2 is a view of the front end of the wrench.

20 Figure 3 is a sectional view through the wrench and showing the same in use.

Figure 4 is a view of the rear end of the wrench.

In this drawing, the numeral 1 indicates an elongated cylinder which is formed with a handle 25 2 at one end thereof and with a thickened part 3 at the other end, the interior part of which is shaped to engage a nut, this interior part being of any suitable non-circular shape, as shown at 4 in Figure 4. An elongated member 5 is 30 formed with the enlarged end parts 6 and 7 which rotatably and slidably support the member 5 in the cylinder 1 and the part 7 is formed with a nut receiving socket 8 and with the tongues or 35 projections 9 which extend from the end of the part 7 and each tongue or projection has a flat inner side and an arcuate outer side, as shown in Figure 4. The part 6 is formed with an eye 10 for receiving a bar or the like which is used for turning the member 5.

40 As shown in Figure 3, this device is adapted to remove the lug nuts A and B or to tighten such nuts, of the lugs of a dual wheel. The nut A is a socketed nut for fitting over the threaded end of a lug and acts to hold a part of the inner

wheel against a part of the lug while the nut B is threaded on the nut A and holds a part of the outer wheel in position. In using the device, it is passed through the outer wheel and the socket 8 is engaged with lug nut A and socket 4 formed 60 by the part 3 is engaged with the nut B. Then a bar is passed through the eye 10 and a piece of pipe slipped over the handle 2 and then by holding one part stationary and turning the other part, either nut may be tightened or loosened. By 65 providing the tongues or projections 9, the nut B can be completely cleared from the nut A before the socket 8 releases its hold on the nut A.

It is thought from the foregoing description that the advantages and novel features of the 70 invention will be readily apparent.

It is to be understood that changes may be made in the construction and in the combination and arrangement of the several parts, provided that such changes fall within the scope of 75 the appended claim.

What is claimed is:—

A wrench of the class described comprising an outer elongated tubular member having a nut receiving socket in one end thereof, a handle 80 connected with the other end, an inner elongated member having enlargements at its ends for rotatably and slidably contacting interior portions of the outer member, an eye forming part at the outer end of the inner member and the other 85 end of said inner member having a nut receiving socket therein, and projections on said last mentioned end of the inner member, each projection having its inner face forming a continuation of a portion of the wall of the socket of said inner 90 member and its outer face of arcuate shape to fit in a portion of the nut engaged by the socket of the outer member, said outer faces of the projections being spaced inwardly from the side 95 walls of the socketed enlargement of the inner member to form a space for receiving the outer end of the nut engaged by the socket of the outer member.
